UNITED STATES PATENT OFFICE.

DAVID J. POWERS, OF CHICAGO, ILLINOIS.

DITCHING-MACHINE.

SPECIFICATION forming part of Letters Patent No. 340,614, dated April 27, 1886.

Application filed July 7, 1884. Serial No. 137,037. (No model.)

To all whom it may concern:

Be it known that I, DAVID J. POWERS, a citizen of the United States, residing at Chicago, in the county of Cook and State of Illinois, have invented certain new and useful Improvements in Ditching-Machines, of which the following is a specification.

My invention relates to improvements in ditching-machines; and it consists, first, in several improvements of the buckets and their appliances calculated to simplify and cheapen their construction, and also to more effectually secure their delivery of tenacious or sticky material, and, further, to secure the delivery of the earthy material at the desired point upon the dump-board, as more fully described in the specification; secondly, in appliances for taking up the rope cable as it is delivered from the spool pulley upon the axis of the ditching-wheel; thirdly, in the adaptation of a follower behind the ditching-wheel in such a manner as to leave a clean ditch into which to place the tile behind the follower or through a vertical opening in the rear of the follower; fourthly, in several subordinate devices, all as fully set forth in the specification.

I have illustrated my invention by the accompanying drawings, in which Figure 1 is a side elevation of the entire machine. Fig. 2 shows the opposite side of the machine. Fig. 3 shows the machine in the ground together with the follower and bridge. Fig. 4 is a transverse sectional view of the bucket, rake, and dump-board. Fig. 5 is a separate and enlarged view of the rake and roller arm. Fig. 6 is a view of one of the diggers or colters. Fig. 7 is a view of the take-up spool and its appendages. Fig. 8 is one of the friction-roller heads of the spools. Fig. 9 is a plan view of the take-up or sheave wheels. Fig. 10 is a side view of the same. Fig. 11 is a sectional side view of the pulley-and-belt device that drives the take-up spool. Fig. 12 is a sectional plan view of the same. Fig. 13 is a perspective view of the bucket, diggers, and guide-rod. Fig. 14 is a longitudinal vertical central sectional interior view of the bucket, showing the application of the interior plate. Fig. 15 is a plan view of the entire machine at work. Fig. 16 is another style of take-up spool operated laterally by a returning-screw.

Like letters and figures refer to corresponding parts in the specification and drawings.

The main frame A is mounted upon wheels B, upon axles C, with tongue D and hounds E, said frame being about the same width as a lumber-wagon, and the axles somewhat longer than in wagons.

Upon the inside of stringers A, and about three feet each way from their centers, are secured rigidly by bolts four uprights, F, extending from slightly below said stringers upward about four and one-half feet. Upon the opposite sides of these uprights are secured metallic plates f, with their edges extending inward about one inch farther than the inner face of the upright, and thus forming ways in which to secure the vertically-sliding frame G, which is composed of four posts, g, and eight cross-girts, g' and g'', so proportioned that the external sides of the posts fit loosely in the groove formed upon the uprights F by plates f, so that the frame G can be raised or lowered by means of sheaves h, chains I, winding-shaft H, with chain-pulleys K upon its ends, and worm-wheel L, secured upon shaft H, between them, and worm and crank-shaft M, with which to operate the same.

Upon the under girts, g', at their central part, is journaled in suitable boxes a transverse shaft, N, of the same length as the width of the frame G.

Upon shaft N is secured the ditching-wheel O, which is composed of radial arms P, secured to a disk, p, upon the shaft. To these arms is attached a gear-rim, Q, and upon the outer ends of the arms are formed buckets R, composed of a front steel cutting-edge, S, in the form of a loop, being about four inches wide and one-fourth of an inch thick, (more or less,) and of a sufficient length to admit of their being firmly secured upon arms P with screws or otherwise. To these front loops, which have the right form to cut a ditch about six inches wide at bottom and flaring upward to a width of nine inches, are attached metallic sides T and T', extending backward in a curving form a proper distance for a suitable-sized bucket, and properly attached to a rear block, R', which forms the back end of the bucket. The sides T' are also attached to wood segments V, secured to the wheel-arms P.

Upon the periphery of the bucket are secured longitudinal metallic bars r , of about one-fourth of an inch in thickness and one and one-fourth of an inch in width, with spaces between them and between them and the plates T and T' of about three-eighths of an inch wide. Plate T' is considerably narrower than plate T , and has a section or door, y' , hinged to it, making it of about the same width as plate T . In side of this bucket is an inclined back, x , adapted to discharge the contents of the bucket upon an inclined shelf, Z , attached to the sliding frame G at the proper height and position to receive the contents of the buckets successively as the wheel Q is revolved and the buckets brought successively above and past the incline Z . Beneath said incline is secured to sliding frame G a circular rod of metal, y , adapted to keep said sections y' closed at all times, except when they pass above the shelf Z , in which position they are free to be opened by the pressure of the contents of the buckets, or otherwise, until the bucket is emptied, when the section automatically closes.

Upon a vertical shaft, A , journaled in proper boxes upon the sliding frame G , is secured a pinion gear-wheel, Q' , which meshes into the cogs of the gear-rim Q . To the top of this shaft is attached a sweep, B' , extending outward some fourteen feet, and adapted for attaching a horse to give rotary motion to the ditching-wheel. The sweep is constructed with a horizontal and diagonal section, the outer section, B^2 , being secured by bolts to B' in such a manner as to admit of the adjustment of the outer end of B^2 up or down to any desired height, according to the depth of ditch being cut.

Mounted upon the top of the sliding frame G is a rake device, C' , pivoted at its rear end to cross-bar g' , so as to swing freely up and down at its forward end, upon which end is secured a series of long teeth, c , adapted to enter the slotted openings in the periphery of the buckets, and to freely traverse the same longitudinally as the bucket-wheel moves forward. Upon the right-hand side of said wheel, when standing in the rear of the machine, is secured a series of circular cams, D' , corresponding in number to the number of buckets, and co-operating with these cams there is an arm, d , extending down from the rake device, with a roller upon its lower end, which at proper intervals engages with the cams and lifts the rake teeth out of the buckets and carries them up out of the way until the next bucket is ready to receive them.

A turning-button, E' , is adapted to be turned under and hold the rake up out of operation when it is not desirable to use it in cleaning the buckets of sticky material.

When the soil being worked is fine enough to escape through the slotted openings upon the periphery of the buckets, metal plates F' (see Fig. 14) are adapted to be introduced inside of the buckets, having their front ends secured in the space f^2 between the front plate

of the bucket and the slatted bars upon its periphery, and its rear end attached with screws or otherwise to the diagonal block R' , thus making a tight bottom to the bucket, no opening in the periphery of the bucket being necessary to admit of the use of the rake in pulverulent or sandy soils.

Forward of each bucket is secured a digger, G^2 , composed of two colter or plow points, adapted to dig and pulverize the soil forward of the buckets, so that it will readily enter the buckets. The diggers have a somewhat larger outline than the buckets, so as to first encounter any serious obstacles that might otherwise harm the buckets, which are not as strong or easily repaired, if injured, as the diggers. The diggers I usually connect with a base, thus giving them additional strength.

Upon the shaft N , at the right side of the wheel, is secured a pulley, G' , of concave outline, and around this pulley several turns of a rope cable, H' , are made, the forward end of which extends ahead of the machine one or two hundred feet, and is attached to an anchor, while the rear end of the cable extends back to a pair of sheave-wheels, J' and J^2 , between which it is grasped. Said sheave-wheels are geared together, and upon the shaft of J' is a sprocket-wheel, J^3 , and a corresponding one upon shaft N , which is connected by a proper chain belt, J^4 . Being connected, as described, with the main shaft, the sheaves J' J^2 take up the cable as it unwinds from the pulley G' and keep it tight upon said pulley, causing the machine to advance toward the anchor as the ditching-wheel rotates. As the rope travels through the sheaves it is finally taken up upon spool K' , which is caused to rotate by belt L' and pulley L^2 upon its shaft and pulley M' upon the main shaft N , the belt being slack enough to allow it to slip upon the pulleys more or less as the spool increases in size.

The spool is made to travel forward and back longitudinally upon its axis, so as to wind the cable evenly upon it by means of the reversing-screw N^2 upon its axis, or by friction-roller devices O' , adapted to give the spool a free and easy motion laterally upon its axis. The screw device in most cases will be found preferable.

In the rear of the machine a follower, X , is adapted to follow in the ditch, and to catch upon its inclining front, X' , all earthy material that may follow the wheel over back. All such accumulating material slides down the slope X' , and is taken up by the buckets of the wheel and carried forward and discharged with other contents of the buckets.

Back from the pitch-board I extend side wings, X^2 , to keep the banks from caving until the tile are laid in place, the same being inserted down through the open space between the wings by hand or otherwise. Behind the follower is a bridge, X^3 , adapted to cover the ditch, so that the horse can pass over it. The bridge and follower are pulled along by the

machine by a chain conneetion, y^2 , or other wise.

To operate the machine an anchor of any usual kind is secured to the ground as far forward of the machine as a cable from one hundred and fifty to two hundred feet will permit. A cable—about a one-inch-in-diameter rope—is passed back from the anchor through an eye upon the forward end of the tongue of the machine, then about four turns around the pulley G' upon the axis of the ditching-wheel, then between the take-up sheave-rollers J' and J'' , and then its end is secured to the body of the spool K' . Then the machine is put in motion by the horse upon the sweep-bar, when the cable tightens upon the pulley G' , and the slack is taken up by the sheave-wheels J' and J'' and spool K' , and the machine is thus caused to feed forward, the cable being wound up upon the spool K' as it passes through the machine by the belt L' , which is so adapted to the pulleys that as the spool enlarges it is modified in its motion by the slipping of the belt upon its pulleys, so as to only take up the cable as fast as it is fed to it by the sheave-wheels. As the machine is fed forward by the cable, the operator lets down the wheel into the ground to the required depth by a backward rotation of the worm M upon the worm-wheel I . As the machine is thus let into the ground and advanced forward, the diggers pulverize and loosen the soil and turf, and the buckets following after take up the loose earth and carry it upward above the dumping board Z , where the door y' is released, and the contents of the bucket are discharged upon the dump Z , the door being opened by the pressure of the material within, or otherwise, and automatically closed when the contents are discharged by the guide-rod Y , which keeps it closed in its entire circuit, except when it is above the dump-board. To insure the certain discharge of clayey or sticky soils from the buckets, the rake C' is adapted to fall into and sweep through the entire length of the buckets, and then to be elevated by the cams D' upon the wheel, so as to take it over the diggers to the next bucket, and so on. When it is not necessary to thus rake the buckets, the rake is elevated above the action of the cams and secured there by turning the button E' under it, and vice versa when the rake is to be used. On the other hand, when working light or sandy soils which may escape through the slatted openings of the buckets, in such case the thin metallic plates T' are applied inside of the buckets, and they are thus made tight. Before proceeding so far with the machine as to bring the left hind wheel of the machine in contact with the bank of earth thrown out of the ditch, it is necessary to extend the axle-tree V' and wheel outward (as seen in Fig. 15) so that it will run outside of the bank of earth. The axle is so constructed that the left-hand section of it with the wheel can be thus readily extended within the iron clasps that secure it

to the machine; or a supplemental axle like V' may be used. After the ditch is started the bridge is placed over it for the better passage of the horse, and when the ditch is down to its depth the follower X may be inserted when working soils that are liable to cave or fall in. Both bridge and follower are attached to the machine to give them their forward motion. As the machine moves forward, it leaves a clean bed ditch within the open rear part of the follower, in which the tile can be placed in proper position, one by one, by the attendant of the machine without materially interfering with his other duties, and thus the work is practically completed before any harm can come to the ditch. Instead of a follower with an open rear extension, through which to insert the tiles in ground that will not cave, I use a follower having only the front section, adapted only to catch and return the earth that follows over again to the under side of the wheel upon the incline X' . When the machine has caught up with the anchor, and it is necessary to take the anchor ahead for further work in the same direction, the cable is freed from the pressure by the take-up wheels, and the belt is released upon the spool pulley. Then the cable can be drawn ahead with the anchor by the draft of the horse upon the anchor, and when the anchor is again attached to the ground the machine is ready to start ahead again the same as at first.

Having thus described my invention, what I claim, and desire to secure by Letters Patent, is—

1. A ditching-machine bucket with a longitudinally-slatted periphery, in combination with a rake device co-operating therewith, substantially as and for the purpose specified.

2. A ditching-machine bucket having a slatted periphery, in combination with a closing-plate, F' , substantially as and for the purpose specified.

3. In a ditching-machine, the combination, with the pivoted rake device C' , provided with a dependent lever, d , of the wheel O and its slatted buckets, and cam-pieces D' , for operating the rake-lever, substantially as shown and described.

4. In a wheel ditching-machine adapted to be moved forward to its work by a rope or cable, the combination, with the excavating-wheel axle having the propelling-cable spool mounted thereon, of a winding-drum for the surplus rope, automatically operated from the axle, substantially as shown and described.

5. In a wheel ditching-machine adapted to be moved forward to its work by a rope or cable, the combination, with the excavating-wheel axle having the propelling-cable spool mounted thereon, of a winding-drum for the surplus rope, and take-up sheave-wheels intermediate between the axle and winding-drum, substantially as shown and described.

6. In a ditching-machine adapted to be moved forward to its work by a rope or cable, the combination, with the bucket-wheel hav-

ing a pulley-axle and means for revolving the same, of sheave-wheels and a winding-spool, both receiving motion from the pulley-axle, whereby when the cable tightens upon the said 5 axle the slack is taken up by the sheave-wheels and wound upon the spool, substantially as shown and described.

7. In a ditching-machine adapted to be moved forward to its work by a rope or cable, 10 the combination, with the bucket-wheel having a pulley-axle and means, substantially as described, for rotating the same, of a winding-spool receiving motion from the pulley-

axle, the sail receiving-spool being adapted to traverse back and forth and wind up the 15 cable as the latter is delivered to it, substantially as shown and described.

8. In combination with a wheel ditching-machine, the follower X, having an inclined front or pitch-board, X', and side boards, X', 20 substantially as described.

DAVID J. POWERS.
